LEVI S. LONGENECKER, OF WASHINGTON, DISTRICT OF COLUMBIA, DEDICATED, BY
MESNE ASSIGNMENTS, TO THE PEOPLE OF THE UNITED STATES.

SEPARATING ROTOR.

1,427,001.

Specification of Letters Patent. Patented Aug. 22, 1922.

Application filed March 11, 1922. Serial No. 543,074.

(FILED UNDER THE ACT OF MARCH 3, 1883, 22 STAT. L., 625.)

To all whom it may concern:

Be it known that I, LEVI S. LONGENECKER, a citizen of the United States of America, and an employee of the Department of Agriculture of the United States of America, residing at Washington, District of Columbia, have invented a new and useful Separating Rotor, of which the following is a specification.

10 This application is made under the act of March 3, 1883, chapter 143 (22 Stat., 625) and the invention herein described and claimed may be used by the Government of the United States, its officers and employees, 15 and by any person in the United States either in public or private work without payment to me of any royalty thereon. I hereby dedicate the same to the free use of the Government and the people of the United 20 States.

The object of my invention is to provide a rotor the purpose and function of which is to cause the separation of heavy from light particles in a current of air or gas in which 25 they are being carried. The invention may be used in a number of ways, such as an aspirator for elevators in dust-removal operations; as a sifting machine; for dockage removal on threshing machines; as a complete dust separator when a bucket type 30 design of vane is used; as a pneumatic method of handling grain, as in an elevator; as a pneumatic way of handling powdered materials, etc.

35 The invention consists substantially in the construction, combination, location and arrangement of parts, all as will be more fully hereinafter set forth as shown in the accompanying drawings and finally set forth 40 in the appended claims.

Referring to the accompanying drawings and to the various views and reference-signs appearing thereon, Figure I is a plan view of the separating rotor, and Figure II is a 45 side view of the separating rotor attached to a fan.

In the drawings, A represents a solid rim-like section supporting the radial sections B to which are attached the vanes C. These 50 vanes may be straight or curved and are made at any angle less than 90 degrees with radial sections B. Vanes C are directly connected to radial sections B or a continuance of radial sections B. The openings D are

located immediately behind the vanes C. 55 The small solid section E is located at the center of the rotor and supports the inner end of the radial sections B.

The main trunk pipe line 1 conveys the particle-laden air or gas to the fan. 2 represents the throat of the fan in which the rotor separator 3 revolves. 7 is the fan casing inclosing the fan 5. 5 is the movable fan element which causes the air or gas to move at a certain velocity. Moving at this 60 velocity it is capable of carrying particles of certain size and weight. This aggregate then hits the moving rotor 3, which derives its rotation from the fan 5, with a certain impact. If this impact is great enough to 65 cause sufficient friction between the rotor and the particles, they will then receive their motion from the rotor and be thrown back or off tangentially into the chamber 4, from whence the particles are conveyed by means 70 of gravity into a suitable receptacle (not shown). The air or gas being very light will, upon hitting the rotor 3, cause very little friction, hence receive little or no imparted force from rotor. It will then continue on through the openings D of the rotor 75 3, the fan 5; and out through the fan outlet or discharge opening 6. It is at once apparent that the line of separation between the discharge in chamber 4 and the discharge 80 in opening 6 is directly determined by some relation which exists between the velocity of the aggregate and the periphery speed of the rotor vanes. Both the velocity and the periphery speed are variables which can 85 be changed at will by suitable changes in the construction. By this means it is evident that a wide variety of separations may be secured, which are equivalent to similar 90 separations as made by sifting with different 95 size sieves.

The air and particles in pipe 1 are in a thoroughly mixed condition and moving with the same velocity through the pipe towards the rotor 3. This mixture, moving 100 through the throat of the fan 2, comes in contact with the fast moving vanes C of the rotor 3. The heavier particles, having considerable weight, strike against the vanes C with considerable force, which in turn creates enough friction on the vanes C so that the rotor can by this medium impart some 105 of its motion to them. This imparted mo-

tion is great enough to counteract the pull exerted by the velocity of the air, which results in whirling them off into the settling chamber 4. The air and smaller particles 5 of dust being very light strike vanes C with little or no friction, hence rotor 3 imparts little or no motion to them, the result being that the air and dust are forced through the openings D in rotor 3, and then caught on 10 the fan paddle 5 and pushed on out the discharge opening 6. As the velocity is increased, the rotor construction remaining the same, the dust or smaller particles discharged with the air through opening 6 will 15 increase in size and weight. The size and weight of these particles can also be increased or decreased by cutting away or adding to the vanes C.

It is obvious that many variations and 20 changes in the details of construction and arrangement would readily suggest themselves to persons skilled in the art and still fall within the spirit and scope of my invention. I do not desire, therefore, to be limited or 25 restricted to the exact construction and arrangement shown and described; but

I claim:

1. In a separator, a conduit, means for 30 creating a stream therethrough of a fluid medium bearing particles to be separated, a rotor mounted in said conduit having apertures for the passage of said fluid medium and having particle-engaging members adjacent said apertures inclined from the 35 plane of rotation of said rotor toward the upstream side of said fluid medium traversing said conduit.

2. In a separator, a conduit, means for 40 creating a stream therethrough of a fluid medium bearing particles to be separated, a disk-rotor mounted in said conduit transversely thereof, said disk-rotor having apertures for the passage of said fluid medium and having particle-engaging members inclined from the plane of rotation of said 45 disk-rotor at an angle causing said particle-engaging members to describe a sweeping action on said particles in a direction transversely of the general direction of movement of said stream through said conduit.

3. In a separator, a conduit, means for 50 creating a stream therethrough of a fluid medium bearing particles to be separated, a rotor mounted in said conduit transversely thereof, said rotor having apertures for the

passage of said fluid medium and radially extending particle-intercepting vanes inclined from the plane of rotation of said rotor toward the up-stream side of said fluid medium traversing said conduit.

4. In a separator, a conduit, means for 60 creating a stream therethrough of a fluid medium bearing particles to be separated, a rotor mounted in said conduit transversely thereof, said rotor having apertures for the 65 passage of said fluid medium and particle-intercepting vanes radially extending from the axis of said rotor, inclined from the plane of rotation of said rotor toward the upstream side of said fluid medium and increasing in area radially outward from said axis.

5. In a separator, a flat disk adapted to 70 be attached to the intake side of a fan, said disk comprising a rim, a section located centrally within said rim, radial sections one end of each of which is secured to said rim and the other end of said centrally located section, vanes attached to the said radial sections at an angle less than ninety degrees therewith, said radial sections and vanes being spaced apart so as to provide openings 75 for the passage therethrough of a fluid medium.

6. In a dust separator, a rotor attached to 80 a fan, said rotor comprising a rim, a section located centrally within said rim, radial sections, one end of which is secured to said rim, the other end of which is secured to said 85 centrally located section, vanes attached to the said radial sections at an angle less than ninety degrees therewith, said radial sections and vanes being spaced apart so as to provide openings 90 for the passage therethrough of air and dust.

7. In a separator, a conduit, means for 95 creating a stream therethrough of a fluid medium bearing particles to be separated, a rotor mounted in said conduit transversely thereof, said rotor having apertures for the 100 passage of said fluid medium and particle-intercepting elements, said particle-intercepting elements each comprising two parts presenting a pocket open to the up stream side of said fluid medium and with one of 105 said parts extending from the other in the direction of and in the plane of rotation of said rotor.

LEVI S. LONGENECKER.
